Primary Examiner — Cathron C Brooks*Assistant Examiner* — W. A. Teddy Falloway(74) *Attorney, Agent, or Firm* — Polsinelli PC(57) **CLAIM**

The ornamental design for a packing tray, as shown and described.

DESCRIPTION

FIG. 1 is a top perspective view of a packing tray according to our new design.

FIG. 2 is a bottom perspective view of the tray of FIG. 1, rotated 180°.

FIG. 3 is a rear elevational view of the tray of FIG. 1.

FIG. 4 is a front elevational view of the tray of FIG. 1.

FIG. 5 is a right end elevational view of the tray of FIG. 1.

FIG. 6 is a left end elevational view of the tray of FIG. 1.

FIG. 7 is a top plan view of the tray of FIG. 1; and,

FIG. 8 is a bottom plan view of the tray of FIG. 1.

1 Claim, 8 Drawing Sheets(56)
